UNITED STATES PATENT OFFICE.

WILLIAM I. GRUBB, OF POTTSTOWN, PENNSYLVANIA.

BICYCLE-PEDAL.

SPECIFICATION forming part of Letters Patent No. 547,639, dated October 8, 1895.

Application filed January 14, 1895. Serial No. 534,931. (No model.)

To all whom it may concern:

Be it known that I, WILLIAM I. GRUBB, a citizen of the United States, residing at Pottstown, county of Montgomery, State of Pennsylvania, have invented certain Improvements in Bicycle-Pedals, of which the following is a specification.

My invention relates to an improved form of pedal for bicycles or similar vehicles, and my main object is to provide a simple and economical construction which will at the same time present a neat appearance and be easily and conveniently maintained in satisfactory working condition.

The invention is fully described in connection with the accompanying drawings, and the novel features are pointed out in the subjoined claims.

Figure 1 is a plan view of a pedal embodying my invention, showing it ready to be applied to a crank-pin and provided on one side with a friction-piece, part of which is broken away. Fig. 2 is a sectional view mainly on the line $x-x$ of Fig. 1, with the friction-piece clamping-screw removed. Fig. 3 is a side elevation showing a portion of the friction-piece broken away and one of the clamping-plates removed. Fig. 4 is a plan view of one of the frame-plates, showing also a portion of the other frame-plate reversed and ready to be moved into engagement with it. Fig. 5 shows one of the friction-piece clamping-plates separate. Fig. 6 indicates a modified form of frame-plate.

The frame of my pedal is made up of two similar plates A and A', both of which may be stamped out of sheet metal with the same punching-dies, subsequently bent up into similar form in the same shaping-dies, and finally united to form the frame by simply reversing and interlocking them.

The punched plate in the flat consists of two parallel strips connected near either end by cross-strips.

Referring particularly to the preferred form, as most clearly shown in Fig. 4 in connection with Fig. 2, in which the bent-up shape is indicated, the longitudinal strips A' A' are flanged outward and the cross-strips a' a' are bent in the opposite direction at the center to semicircular form, as shown at b' b'. The flanged portions have their outer edges ser-

rated, as at f', and their inner edges notched near either end, as at g' g', and the cross-strips are notched, as at d' d', on either side of the semicircular portion b', so as to form a notched joint or halving with the similar reversed plate A, a portion of which is indicated in Fig. 4 ready to be pushed into engagement to form the interlocked frame shown in Figs. 1, 2, and 3. When the reversed plates A and A' are thus interlocked, the oppositely-extending flanged portions form the sides of the pedal-frame, and the oppositely-curved central portions b' b of the cross-pieces of a' a form central openings, through which the crank-pin barrel H passes. The cupped head h of this barrel seats against the faces c² c³ of the interlocked plates, which faces are drawn flush with each other by means of the screw-cup E, which engages the opposite end of the barrel. The cupped head h of the barrel is notched at h' to engage the projected edges c' c of the cross-strips a' a, so as to positively prevent rotation of the barrel and rigidly connect it with the frame-plates, while at the same time rigidly uniting the latter.

The serrated edges f f' form a foothold, which it is preferable to supplement by a friction-piece of rubber or similar material. This I accomplish in a simple manner, as follows: The notches g in the meeting edges of the plates when brought together form openings or perforations g², Fig. 3. These openings receive the flanged heel-pieces m, formed at one end of two similar clamping-plates M, the opposite ends of which have semicircular recesses m' in their meeting edges at the center of the pedal, which together form a circular opening for the passage of a clamping-bolt N, the head of which is seated equally on each of the clamping-plates, while the body passes through an intermediate friction-piece K and through the opening e e' formed in the side of the pedal-frame. I am thus enabled to firmly secure friction-pieces to the frame or to remove the same by means of a single bolt.

In the modified form of plate indicated in Fig. 6 the reversed plates are united by pushing the single concaved cross-bar a⁶ of one plate through the slot at a⁵, between the cross-bars a⁴ a⁴ of the other plate, the crank-pin barrel passing through the central opening formed by the combined plates.

Having thus fully described my invention, I do not desire to limit myself to the exact construction shown; but

What I claim is—

- 5 1. A bicycle pedal frame comprising two plates each formed with parallel longitudinal strips and connecting cross strips, said longitudinal strips being bent or flanged outward and the cross-strips of one plate adapted to 10 interlock with those of the second when reversely arranged, substantially as and for the purpose set forth.
- 15 2. A bicycle pedal frame comprising two plates each formed with parallel longitudinal strips and connecting cross strips the longitudinal strips being bent or flanged outward and the cross strips of each plate being similarly slotted so as to interlock with a longitudinal movement when brought together in 20 reversed position substantially as and for the purpose set forth.
3. A bicycle pedal comprising two similar plates flanged at each side and having cross strips reversely bent into semicircular form

midway between the flanged sides and provided with notches or slots $d' d'$ whereby the reversed parts are interlocked, and a barrel or sleeve passing through the central opening and provided with a head seating against the edges of the abutted plates and with a notch 30 engaging the same to prevent any turning of the barrel in said central opening substantially as and for the purpose set forth.

4. In a bicycle pedal the combination with a pedal frame having the side thereof provided with a perforation near each end, of a rubber or other friction piece secured thereto by means of two clamping plates each having a heel engaged in one of said perforations and the abutting edges engaged by a clamping 40 bolt, substantially as and for the purpose set forth.

In testimony whereof I affix my signature in presence of two witnesses.

WILLIAM I. GRUBB.
